SHEET-HANDLING MECHANISM FOR PRINTING PRESSES

Otto C. F. Meisel, Milton, Mass., assignor to Meisel Press Manufacturing Company, Boston, Mass., a corporation of Massachusetts

Application December 18, 1931
Serial No. 581,806

14 Claims. (Cl. 91—16)

This invention relates to sheet-handling mechanisms such as are incorporated in printing presses for handling the sheets after impression, and the object is to provide an improved construction of such mechanism particularly applicable to cases where the printed matter is subjected to some further treatment as, for instance, by spraying it with wax as is commonly practised in the case of glassine wrappers.

10 My invention will be well understood by reference to the following description of the illustrative embodiment thereof shown by way of example in the accompanying drawings, wherein:—

Fig. 1 is a diagrammatic side elevation of part 15 of a press embodying my invention;

Fig. 2 is a detail of a driving train of gears utilized therein and is a section of the further side of the further frame, viewing Fig. 1;

Fig. 3 is an enlarged section just to the rear 20 of the nearer frame in Fig. 1 showing the greater part of the mechanism in elevation and with parts broken away;

Fig. 4 is a broken vertical section on the line 25 4—4 of Fig. 3;

Fig. 5 is a fragmentary section on an enlarged scale on the line 5—5 of Fig. 4; and

Fig. 6 is an enlarged section on the line 6—6 of Fig. 5.

Referring to Fig. 1 of the drawings, I have 30 there partially shown a multi-color press having an impression cylinder 7 having grippers 9 by means of which sheets are carried beneath the cooperating plate cylinders 11, two of which are shown in the figure. From the impression cylinder 35 the sheets are delivered to grippers 13 of a skeletonized drum 15, of which the construction, environment and cooperation with the other elements of the press are more particularly the subject matter of my invention. The sheets are carried 40 around this drum in a counterclockwise direction, viewing Fig. 1, and are here shown as being delivered therefrom to an accumulating cylinder 17 from which in turn they pass to the fly sticks 19 to be delivered on table 21. I have 45 herein shown the drum 15 and the mechanism to which it delivers the sheets as well as the inking mechanisms for two of the plate rolls 11 as mounted on a subsidiary framework embodying the side frames 21 and 23 (Fig. 4) shiftable on the ways 25 so that they may be moved to the 50 right, viewing Fig. 1, away from the impression cylinder. The impression cylinder is thus exposed so that make-ready may be effected and other advantages are obtained which will appear.

55 Referring now to Figs. 3 and 4, the preferred

form for the skeletonized drum 15 here shown comprises a pair of ring gears 27 having external teeth and open centers, these gears herein being suspended at the inner sides of the frames 21 and 23 respectively by the rollers 29 carried on 60 studs projecting inwardly from the frame and engaging the inner circumferences of the gears. Extending between these gears are suitable cross members, certain of which, as that marked '31 at the upper left hand portion of Fig. 3, carry 65 the abutments 33 with which cooperate the gripper fingers 13. The operating means for these grippers may be of any suitable construction, such as that partly illustrated in the drawings and comprising the segment gears and levers 70 mounted on fixed centers on the ring gears and adapted to cooperate with adjacent fixed actuating cams in the usual manner. The gripper mechanism may preferably be enclosed in a metal casing 35, the showing of which in Fig. 3 indicates 75 the four sets of grippers in the illustrative embodiment of the invention.

The sheet taken from the impression cylinder by the gripper in the position shown in Fig. 1 is 80 carried around the drum counterclockwise as the ring gears rotate and delivered to the accumulating cylinder 17 with the printed surface facing 85 inwardly. To support the sheet in the path of the grippers I may provide the segments 37 supported on the cross rods 39 extending between 90 the two ring gears, which segments are adapted to make contact with the inner surface of the sheet in localized areas, such as the margins or the like where there is no printing. A suitable 95 form for these segments may be that shown in detail in Figs. 5 and 6 wherein they are illustrated as of T section having the flange of the T presented to the sheet and preferably formed with pointed teeth 41 as shown. These segments are 100 adjustable axially of the drum so that they may make contact with the sheet in desired places and are herein shown as secured by means of the screw clamps 43 in desired position on the cross members 39.

To support the sheet externally and for other purposes which will appear, the skeletonized drum so far described is housed within a sheet metal casing closely conforming thereto and embodying end or base sections 45 secured to the 105 inner sides of the frames 21 and 23 and a peripheral cylindrical portion 47 closely opposing the path of the grippers. The cylindrical portion is interrupted along lines corresponding to elements of the cylinder to provide for entrance of a sheet 110 to the casing from the impression cylinder 7 and

exit therefrom to the accumulating cylinder 17. It may also be slotted to permit the gears 49 (Fig. 3) on cross shaft 51 to project therethrough to mesh with the ring gears 27 for driving the latter but otherwise preferably substantially completely encloses the skeletonized drum. As seen in Fig. 3, one segment of the cylindrical portion 47 of the casing may be hinged at 53 and normally secured in position by a latch 55 so that when 10 the auxiliary frame is drawn back away from the impression cylinder toward the right in Fig. 1, this section may be dropped down providing convenient access to the exterior of the drum.

Since the ring gears have open centers and 15 are supported by their inner periphery and driven at their outer periphery, they may turn freely about stationary connections extending through their open central portions to the interior of the drum. Thus a spraying mechanism 57 may be 20 provided for spraying wax on the printed surface of the sheet having a pipe connection 59 extending out through an end wall 45 of the enclosing casing within the interior circumference of the ring gears 27. A blower connection 61 may also be provided 25 through the casing to withdraw from the interior of the drum the superfluous mist or vapor of the wax. I have herein shown these connections as being through the further base of the sheet metal enclosing casing, viewing Figs. 1 and 30 3, and preferably the greater portion of the other base takes the form of a removable cover 63 having a handle 65 and aligning with a corresponding large opening 67 in frame 21 (see Fig. 4), thus providing a man-hole through which easy 35 access is had to the interior of the drum.

To facilitate the cleaning from the drum and the interior of the casing of any residual deposited wax I may offset a portion of the enclosing casing 47, as seen at the right of Fig. 3 at 69, 40 to receive a gas burner 71. When this is lighted, the interior of the casing soon becomes sufficiently heated to cause the wax deposited thereon and on the cylinder to melt and flow down so that it may be easily cleaned out. If desired, a drain 73 45 may be provided at the bottom of the casing for this purpose. The gas burner 69 may also be utilized in proper instances to dry the ink impression on the sheets as, for instance, would be desirable if the press were utilized to print regenerated cellulose or so-called cellophane.

As seen from Fig. 2, the skeletonized drum 15 may have a positive gear connection with the impression cylinder and other parts of the press. Thus, referring to Fig. 2, I have there shown gear 55 75 on the shaft 77 of the impression cylinder 7 connected by idler 79 to gear 81 on shaft 51 which carries the gears 49 (see Fig. 4) which drive the ring gears 27 and this in turn may be connected by idler 83 to gear 85 on the shaft 87 of the accumulating cylinder 17, thus providing a positive and accurately timed connection between the elements of the press. The provision of the sheet-handling means in the form of a rigid drum permits the parts to move accurately and rapidly and without troubles due to wear. Since the path of the grippers is of fixed curvature and the ring gears provide a rigid support adjacent this path, a simple and efficient design of grippers is made possible.

70 I am aware that the invention may be embodied in other specific forms without departing from the spirit or essential attributes thereof, and I therefore desire the present embodiment to be considered in all respects as illustrative and not restrictive; reference being had to the appended

claims rather than to the foregoing description to indicate the scope of the invention.

I claim:

1. In combination with a printing cylinder, 80 means for receiving and treating the printed sheet comprising a casing apertured for the entrance and exit of the sheet, a skeletonized drum revolving in the casing to receive the sheet and support the same by contact with limited areas of its inwardly presented printed surface, said drum having an open end and a fluid spray within said drum having a connection through said open end whereby the drum may revolve freely thereabout.

2. In a mechanism for delivering printed sheets, a skeletonized drum having open ends, 90 means engaging the same adjacent the periphery for rotatably supporting the drum, means for driving the drum engaging the same adjacent its periphery, means carried by the drum for holding sheets, and a fluid spray within the drum having a connection extending through an open end.

3. In combination with a printing cylinder, 100 means to receive work therefrom, constituting a skeletonized cylinder over which it may pass with the printed surface inward, comprising a pair of ring gears, means engaging a periphery thereof for suspending the same, means extending between the same to engage the work at spaced points and support the same in the cylindrical surface, a fluid spray within the cylinder having a connection extending through the center of one of said gears, and means for driving the gears.

4. In combination with a printing cylinder, 110 means to receive work therefrom, constituting a skeletonized cylinder over which it may pass with the printed surface inward, comprising a pair of ring gears, means engaging a periphery thereof for suspending the same, means extending between the same to engage the work at spaced points and support the same in the cylindrical surface, a fluid spray within the cylinder having a connection extending through the center of one of said gears, a housing substantially 115 entirely enclosing said skeletonized cylinder but interrupted along lines corresponding to elements thereof to provide for the entrance and exit of the work, and means for driving the gears.

5. In a mechanism for delivering printed sheets, a skeletonized drum having open ends, 120 means engaging the same adjacent the periphery for rotatably supporting the drum, means for driving the drum engaging the same adjacent its periphery, means carried by the drum for holding sheets, a fluid spray within the drum having a connection extending through an open end, and a housing substantially entirely enclosing said drum but interrupted along lines corresponding to elements thereof to provide for the entrance and exit of the work.

6. In combination with a printing cylinder, a mechanism for delivering printed sheets therefrom comprising a skeletonized drum comprising 130 a pair of ring gears, means extending between the same for holding the sheet and for supporting it by contact with limited areas thereof, means for driving the gears, a housing substantially enclosing said cylinder, but interrupted to provide for entrance and exit of the sheet whereby 140 to provide an enclosure for maintenance therein of an atmospheric condition substantially different from that at the exterior, said housing having a removable end providing for access to 145 the interior of said drum.

7. In combination with a printing cylinder, a mechanism for delivering printed sheets therefrom comprising a skeletonized drum comprising a pair of ring gears, means extending between the same for holding the sheet and for supporting it by contact with limited areas thereof, means for driving the gears, a housing substantially enclosing said cylinder, but interrupted to provide for entrance and exit of the sheet, where-
10 by to provide an enclosure for maintenance therein of an atmospheric condition substantially different from that at the exterior, said housing having a removable end providing for access to the interior of said drum and including a shift-
15 able segment providing access to the exterior. 80
8. In combination with a printing cylinder, means for delivering sheets therefrom comprising a frame movable to and from said cylinder, supports carried by the frame, ring gears sus-
20 pended on said supports, means extending be-
tween the same for holding the sheet and for supporting it by contact with limited areas thereof, means for driving the gears, a housing sub-
25 stantially enclosing said cylinder, but interrupted to provide for entrance and exit of the sheet, said housing having a shiftable segment exposed when said frame is moved away from the cylinder pro-
viding access to the exterior of the drum. 85
9. In combination with a printing cylinder, a mechanism for delivering printed sheets there-
30 from comprising a drum comprising a pair of open-centered annuli, means for rotatably sus-
pended them at one circumference thereof, gripper means carried by said annuli for engaging
35 sheets transferred thereto with their printed faces inward, and means for supporting the sheet so held in the path of the gripper means arranged to make contact with the sheet in limited localized areas. 90
- 40 10. In combination with a printing cylinder, a mechanism for delivering printed sheets there-
from comprising a drum comprising a pair of open-centered annuli, means for rotatably sus-
pended them at one circumference thereof, gripper
45 means carried by said annuli for engaging sheets transferred thereto with their printed faces inward, means for supporting the sheet so held in the path of the gripper means arranged to make contact with the sheet in limited localized
50 areas, and stationary supporting means closely opposing the cylindrical portion of said drum. 95
11. In combination with a printing cylinder, a mechanism for delivering printed sheets there-
55 100
- 60 12. In a mechanism for delivering printed sheets from a printing mechanism a drum comprising a pair of annuli, means for rotatably suspending them at one circumference thereof, members extending between them, gripper fingers cooperating with certain of said members to clamp sheets thereto with their printed faces inward, and segments supported by others of said members for supporting the sheet in the path of said grippers by contact with limited areas of the printed interior faces thereof. 105
13. In combination with a printing cylinder, means to receive work therefrom, constituting a skeletonized cylinder over which it may pass with the printed surface inward, comprising a pair of ring gears, means engaging a periphery thereof for suspending the same, means extending between the same to engage the work at spaced points and support the same in the cylindrical surface, a housing substantially entirely enclos-
110 ing said skeletonized cylinder but interrupted along lines corresponding to elements thereof to provide for the entrance and exit of work, means for driving the gear and means having a connec-
115 tion extending through said housing at the open centers of the gears for controlling conditions within the housing. 113
14. In combination with a printing cylinder, means to receive work therefrom, constituting a skeletonized cylinder over which it may pass with the printed surface inward, comprising a pair of ring gears, means engaging a periphery thereof for suspending the same, means extending between the same to engage the work at spaced points and support the same in the cylindrical surface, a housing substantially entirely enclos-
120 ing said skeletonized cylinder but interrupted along lines corresponding to elements thereof to provide for the entrance and exit of work, said housing providing an enclosure wherein an at-
125 mospheric condition different from that exterior thereto may be maintained, and means for driv-
ing the gears. 125
